4 Claims. (Cl. 266—5)

My present invention relates to a method of and an apparatus for heat-treating metals and, more particularly, to annealing apparatus of the dome or hood type.

Hood-type ovens for the annealing and heat treatment of round metallic bodies, such as sheet-metal coils and the like, have been provided heretofore with a furnace housing adapted to be disposed upon a base supporting the material to be treated with annular clearance whereby heating means (e.g. burners) may be disposed in this clearance. Usually a protective gas containing at most minimal quantities of oxidizing constituents is circulated around and/or through the coils for bringing them to the proper temperature. Since this protective gas was only limitedly heated by its contact with the furnace walls, it had been proposed to provide additional heat-exchange surfaces which project radially inwardly from the housing to effect a more rapid heating of the gas. This was particularly important in open-coil arrangements wherein the gas passed between individual turns of the coil and was, in effect, a heating fluid. These heat-exchange surfaces have been found to be only limitedly effective. Another disadvantage of known annealing furnaces of the character described was that the heating means radiated heat directly onto a juxtaposed surface of the body whose temperature was thus raised inordinately higher than the desired treatment temperature while other portions of the body remained at temperatures below that usually required for the heat treatment. This nonuniformity of heating cannot, for the most part, be avoided in hitherto existing heat-treatment apparatus.

It is an object of the present invention to provide a method of heating metal bodies whereby the aforementioned disadvantages may be obviated.

It is another object of this invention to provide an improved hood-type annealing oven whereby metal bodies can be heated substantially uniformly to the appropriate heat-treatment temperatures.

According to one aspect of this invention a body to be heated is disposed with clearance within a heated furnace chamber and a protective gas is circulated around the body and through the clearance while an apertured conductive layer is interposed between the heating means and the body for preventing excessive heating of those portions of the latter upon which the radiant energy of the heater would otherwise impinge directly. The protective gas can thus pass through the interstices of the conductive layer and is, consequently, heated by contact therewith over a considerable surface area to serve as a heating fluid. Advantageously the apertured layer, which may be a metal screen, grate, perforated plate, array of bars etc., is provided with portions extending within the clearance generally transversely to the direction of displacement of the gas stream. This arrangement increases considerably the thermal efficiency of an annealing furnace, without requiring unusually high gas velocities, as a consequence of the large heat-transfer area presented by the apertured layer. Moreover, this layer functions as a Davy heat shield inasmuch as it conducts radiant energy away from hot spots to equalize the temperature within the furnace.

According to another aspect of the invention, an apparatus for treating metal bodies and, particularly, for

2

the heat-treatment of cylindrical or round objects comprises a housing surrounding these objects with peripheral clearance and heating means at, at least, one wall of the housing confronting a surface of the objects to be heated; circulating means is provided for continuously passing a protective gas (e.g. an inert or reducing gas) through this clearance and around the bodies to be heated. A heat-conductive perforate shield is disposed around the body intermediate the latter and the heating means which may comprise exposed gas burners or the like and/or a radiant-heating body such as a mantle or partition. The shield is provided with portions extending generally transversely to the direction of propagation of the gas and may be formed from wire mesh, bars or the like which span substantially the entire clearance in the transverse direction. The heat shields also constitute turbulence promoters capable of effecting a substantial increase in the heat-transfer characteristics of the furnace. While, in general, it is desirable to interpose the heat shield directly between the furnace wall and the body to be heated, in which case the body itself may form with the housing an annular compartment for the passage of the heating fluid, it is also possible to form this compartment by means of a partition interposed between the body and the furnace wall. In the latter case the apertured layer is disposed between this partition and the wall.

Advantageously the apertured layer can be a woven wire cloth or a wire netting which is corrugated transversely to the direction of flow of the gas and which thus spans the entire width of the compartment. It should be noted, however, that perforated corrugated sheet metal can also be employed in this connection while wire dust filters are also suitable. The corrugated material preferably contacts both the wall of the furnace and the confronting surface forming the compartment therewith. When a partition is dispensed with, the corrugations abut the body directly. The apertured layer may also be so constructed that direct radiation between the furnace wall and the body is prevented. The mesh of the wire screen and the thickness of the wires constituting it are so selected as to effect an optimum heat transfer when considering both impediment to fluid flow and heating effect.

The above and other objects, features and advantages of the present invention will become more readily apparent from the following description, reference being made to the accompanying drawing in which:

FIG. 1 is an axial cross-sectional view of a hood-type annealing oven according to the invention;

FIG. 2 is a perspective view, drawn to an enlarged scale, of the heat shield of this oven;

FIG. 3 is a cross-sectional view taken along the line III—III of FIG. 1;

FIG. 4 is a similar cross-sectional view, with parts broken away, showing another oven;

FIGS. 5 and 6 are fragmentary perspective views illustrating other embodiments of the invention;

FIG. 7 is an elevational view of a further apertured layer; and

FIG. 8 is a perspective view illustrating still another layer.

FIG. 1 shows an annealing furnace 10 for stacked coils B of sheet metal to be annealed by the open-coil method. The furnace comprises a circular base 1 which is formed with a plurality of concentric annular channels 11 containing a sealing fluid such as water. This concrete base 1 carries a pedestal 12 composed of ceramic blocks upon which a motor 13 and its blower 7 are mounted. Blower 7 is of the axial-intake and radial-outflow type and supplies a protective gas to a plurality of radial heat channels 14 which carry this gas into an annular clearance 8 between the furnace wall 2 and the

coils B. The furnace housing formed by this wall 2 and a cover 3 is generally cylindrical and can be lifted from the base 1 by means of lugs 15. The furnace housing 2 and mantle 18 also carry a conical plate 16 from which axially extending flanges 17 depend. These flanges project into the liquid contained in respective channels 11 and prevent the escape of gases from the furnace.

The mantle or liner 18 is of refractory material and is spaced from the housing 2, forming therewith an annular compartment 4 for gas burners 6 or any other suitable heating means. The partition 18 constitutes a so-called "radiating hood" for emitting thermal energy in the direction of the bodies B. The latter form with this hood the annular compartment 8 through which the protective gas passes upwardly toward the domed roof 19 of cover 3. A Davy-like mesh 9 of corrugated wire screening forms a heat-transfer layer and heat shield intermediate the radiating partition 18 and the bodies B with the bights of the corrugations in contact with the confronting surfaces 5 and 20 of the partition and the bodies. The corrugations extend transversely to the direction of gas flow as indicated by the arrows. Stakes 21 serve to hold the blocks of pedestal 12 in place.

In operation, the cover 3, via its lugs 22, or the housing 2 is lifted from the base 1 to permit the coils B, whose turns are open to allow passage of gas therebetween, to be placed upon the vanes 23 (see also vanes 23' of FIG. 4). The cover 3 and/or the housing 2 are then replaced and a protective gas introduced via a pipe 25. Burners 6 are then ignited and serve to heat the mantle 18 while the gases are circulated upwardly by blower 7 through the channels 14 and compartment 8, are deflected downwardly by the roof 19 and descend between the turns of coils B and back to the blower 7 past the vanes 23. The corrugated mesh 9 serves to heat the gas by contact and is in turn heated by both radiation and conduction from the mantle 18. The conductive mesh, however, serves to prevent direct irradiation of the bodies B by the mantle 18 and also acts to equalize the furnace temperature in a manner of a Davy screen by conducting heat rapidly away from overheated regions of the furnace. The high surface area of the screen renders it quite capable of maintaining the gas at a suitable temperature. In fact, it has been found that when the temperature in chamber 4 between the partition 18 and the furnace wall 2 is approximately 1000° C. a well-defined gas temperature between 600° and 700° C. results with a consequent uniform heating of the coils B to a temperature between 600° and 700° C. without overheating even at their surfaces proximal to the partition 18. FIGS. 2 and 3 show the corrugated wire screen B in further detail. In the open-coil method the aligned axial passages of the coils are blocked by a plate 44 from throughflow of the gas which is, consequently, forced to flow around each individual turn.

In FIG. 4 I show a furnace, generally similar to that of FIG. 1, for a heat treatment of coils by the closed-coil method. In this case the coil B' is again disposed upon radial vanes 23' but the plate 44 is dispensed with so that the gas passes over the coils into the axial intake of blower 7' whose radial outflow again proceeds through channels 14' as previously described. The mantle 18 is also dispensed with in the embodiment of FIG. 4 so that the transversely corrugated screen 9' is interposed directly between the burners 6' and the coil B'. In FIG. 5 I show an arrangement whereby a grate-like metal shield 25 is disposed between a radiant-heating mantle 18' and the body B to be heated. The grate 25 is provided with apertured portions 26 extending transversely to the direction of gas flow and in contact with mantle 18'. This arrangement functions similarly to the previously described one.

The embodiment shown in FIG. 6 comprises a parti-

tion 27 between mantle 18" and body B which forms with the mantle an annular chamber 28 for the transversely corrugated screen 9" which contacts both the mantle and the partition 27. The gas passes, as indicated by the arrows, through compartment 28 into contact with the bodies B. The apertured shield 30 of FIG. 7 has its perforations 31 inclined to the plate so that direct radiation through these apertures is prevented. An expended-metal shield may also be provided to achieve an identical result. A shield of this type can be used with the structure shown in FIG. 4 wherein the radiating mantle 18 or 18' is dispensed with. Again transversely extending flanges 32, suitably apertured to permit the passage of gas, are provided. The shield 33 of FIG. 8 is corrugated in a manner similar to that described with reference to the screens 9, 9' and is likewise of a thermally conductive metal. Perforations 34 to permit the passage of gas are, of course, provided. It should be noted that none of the heat shields described herein functions to provide a substantial hindrance to the flow of the gas therethrough or results in abnormally high pressure drops within the furnace.

The invention as described and illustrated is believed to admit of many modifications and variations within the ability of persons skilled in the art, all such modifications and variations being deemed to be included within the spirit and scope of the appended claims.

What is claimed is:

1. An annealing oven for sheet-metal coils and the like, comprising a hood-like housing forming a generally cylindrical furnace chamber for a coil to be annealed and surrounding the latter within said chamber with peripheral clearance; partition means in said chamber forming an annular compartment with said housing and confronting said coil within said chamber; burner means within said compartment for heating said partition means; circulating means for passing a protective gas through said clearance and around said coil in said chamber in heat-exchanging relationship with said wall; and a corrugated mesh of thermally conductive wire disposed within said clearance with the corrugations thereof extending transversely to the direction of flow of said gas whereby the openings in said mesh promote turbulence in said gas, said mesh being interposed between said annular partition means and said coil for preventing excessive irradiation of the latter by said partition means.

2. An annealing oven for sheet-metal coils and the like, comprising a hood-like housing forming a generally cylindrical furnace chamber for a coil to be annealed and surrounding the latter within said chamber with peripheral clearance; partition means in said chamber forming an annular compartment with said housing and confronting said coil within said chamber; a plurality of angularly equispaced burners within said compartment for heating said partition means; circulating means for passing a protective gas through said clearance and around said coil in said chamber in heat-exchanging relationship with said wall; and a corrugated mesh of thermally conductive wire disposed within said clearance with the corrugations thereof extending transversely to the direction of flow of said gas whereby the openings in said mesh promote turbulence in said gas, said mesh being interposed between said annular partition means and said coil for preventing excessive irradiation of the latter by said partition means.

3. An annealing oven for sheet-metal coils and the like, comprising a base, a hood-like housing removably positioned on said base, said housing forming a generally cylindrical furnace chamber for a coil to be annealed and surrounding the latter within said chamber with peripheral clearance; a heating mantle in said chamber forming an annular compartment with said housing and confronting a coil within said chamber; a plurality of angularly equispaced burners within said compartment for heating said mantle; a blower centrally disposed within said

chamber for passing a protective gas through said clearance and around said coil in said chamber in heat-exchanging relationship with said wall; a corrugated woven mesh of thermally conductive wire disposed within said clearance with the corrugations thereof extending transversely to the direction of flow of said gas whereby the openings in said mesh promote turbulence in said gas, said mesh being interposed between said annular mantle and said coil for preventing excessive irradiation of the latter by said mantle while contacting both said mantle and said coil; and sealing means between said housing and said base for preventing the escape of gas from said chamber.

4. An annealing oven for sheet-metal coils, comprising a base, a hood-like housing removably positioned on said base, said housing forming a generally cylindrical furnace chamber with vertical axis for a coil to be annealed and surrounding the latter within said chamber with peripheral clearance; a heating mantle in said chamber forming an annular compartment with said housing and confronting a coil within said chamber; burner means positioned within said compartment for heating said mantle; circulating means disposed at the bottom of said chamber for passing a protective gas upwardly through said

5
10
15
20
25

clearance and around said coil in said chamber in heat-exchanging relationship with said wall, said chamber being provided with a roof for deflecting the rising gas stream from said clearance downwardly toward said circulating means through spaces between the turns of said coil; a woven wire mesh disposed within said clearance and provided with horizontal corrugations for intercepting the flow of said gas whereby the openings in said mesh promote turbulence in said gas, said mesh screening said coil from said mantle and minimizing irradiation of the coil by said mantle; and sealing means between said housing and said base for preventing the escape of gas from said chamber.
